(57) CLAIM

The ornamental design for an insole for high heels, as shown and described.

DESCRIPTION

FIG. 1 is a top, left side perspective view of an insole for high heels showing my new design;

FIG. 2 is a top, right side perspective view thereof;

FIG. 3 is a top plan view thereof; and,

FIG. 4 is a left side view thereof.

A bottom side view of the embodiment of the insole for high heels of the present invention is not shown because it forms no part of the invention.

All surfaces not shown form no part of the claimed design.

All sides not shown form no part of the claimed design.

1 Claim, 4 Drawing Sheets

FIG. 1

FIG. 2

FIG. 4
